UNITED STATES PATENT OFFICE.

CHARLES L. DEPOLLIER, OF NEW YORK, N. Y., ASSIGNOR TO DUBOIS WATCH CASE COMPANY, OF BROOKLYN, NEW YORK, A CORPORATION OF NEW YORK.

DESIGN FOR A BOX OR CASE CONTAINING ARTICLES OF JEWELRY.

49,954.

Specification for Design.

Patented Nov. 28, 1916

Application filed October 7, 1914. Serial No. 865,592. Term of patent 3½ years.

To all whom it may concern:

Be it known that I, CHARLES L. DEPOLLIER, a citizen of the United States, residing in New York city, in the county of Kings and State of New York, have invented a new, original, and ornamental Design for a Box or Case Containing Articles of Jewelry, of which the following is a specification, reference being had to the accompanying drawing, forming a part thereof.

The figure is a perspective view of a box or case containing articles of jewelry, illustrating my new design.

I claim:—

The ornamental design for a box or case containing articles of jewelry, as shown.

CHARLES L. DEPOLLIER.
